[57] **CLAIM**

The ornamental design for an advertising sign for vehicles, as shown and described.

DESCRIPTION

FIG. 1 is a top, front perspective view of an advertising sign for vehicles showing my new design;

FIG. 2 is a front elevation view thereof, the rear elevation view being a mirror image;

FIG. 3 is a right side elevation view thereof, the left elevation view being a mirror image;

FIG. 4 is a top plan view thereof;

FIG. 5 is a bottom plan view thereof; and,

FIG. 6 is a cutaway close-up front, top, and left perspective view of the “crown” of the sign.

The broken lines are shown for illustrative purposes only and forms no part of the claimed design.
